UNITED STATES PATENT OFFICE.

HENRY M. QUACKENBUSH, OF HERKIMER, NEW YORK.

TARGET.

SPECIFICATION forming part of Letters Patent No. 761,784, dated June 7, 1904.

Application filed October 30, 1903. Serial No. 179,157. (No model.)

To all whom it may concern:

Be it known that I, HENRY M. QUACKENBUSH, a citizen of the United States, residing at Herkimer, in the county of Herkimer and 5 State of New York, have invented certain new and useful Improvements in Targets, of which the following is a specification.

My present invention pertains to targets, the construction and advantages of which will 10 be hereinafter set forth, reference being had to the annexed drawings, wherein—

Figure 1 is a perspective view of the target; Fig. 2, a transverse sectional view on the line 2 2 of Fig. 1, the cover of the paint receptacle or box being broken away; Fig. 3, a rear elevation of the target with a portion of the supporting bar or plate broken away; Fig. 4, a vertical sectional view on the line 4 4 of Fig. 3; Fig. 5, a similar view showing the position 15 and relation of the roller and cover to the target-face as the roller is raised or lowered; Fig. 6, a perspective view of the roller and its attendant parts as viewed from the rear, and Fig. 7 a similar view of the paint receptacle 20 or box.

The primary object of my invention is to provide a simple and efficient device for effacing the marks made by a bullet upon the face of a target, which device may be operated 25 at a distance from the target.

A further object is to provide means which will effectually protect the effacing-roller and the paint or liquid receptacle from foreign matter and from injury by spent bullets.

30 Broadly stated, the invention comprises a target, a liquid-receptacle located at the base thereof, an effacing-roller or its equivalent, means for passing said roller over the face of the target, and a cover which when the roller 35 is in the receptacle will fully close the latter, the cover in no manner interfering with the action of the roller nor affecting the work of effacement accomplished thereby.

Referring to the drawings, A denotes the 40 body of the target provided with concentric markings, the bull's-eye A', and alarm A'', as usual. Located at the lower portion of the target and preferably secured thereto by screws B or their equivalent is a paint or 45 liquid containing trough or receptacle C, said

receptacle being of a length equal to the width of the target and provided with a recess or cut-away portion D in the upper edge of each end.

E denotes the cover or closure for the receptacle, which cover preferably takes the form shown most clearly in Figs. 1 and 6, wherein it will be seen that the lower outer edge rests upon the front portion of the receptacle, while the upper edge bears against the face of the target when said cover is in its closed position. The upper face of the cover, as will be noted, is given a downward and outward inclination, so that any matters—such as spent bullets, fragments thereof, or any extraneous substance—will tend to pass off the cover. 55

Attached to each end of the cover E is an end piece or closure F, said pieces being of sufficient depth to extend past the upper edge 60 of the ends of the paint-receptacle, thereby effectually closing said receptacle when the cover is lowered. The end pieces also form a support for an axle or pintles G, upon which is mounted a roller H, the pintles passing 65 down into the recesses D when the cover is closed. Said end pieces are extended rearwardly of the body of the target, and a bail or loop I has its laterally-bent ends J passed into openings formed in said rearward extensions. Rolls K, mounted upon said ends J, bear against the rear face of the body of the target. A cord or any other suitable means which can be operated from a point remote 70 from the target may be connected to the bail I for elevating the same and with it the roller and closure, though of course the bail may be operated directly by hand if it should be found desirable so to do. 75

A forwardly-projecting stop L is secured to the upper end of the body and serves to arrest the cover, and consequently the parts attached thereto, when the same has been elevated sufficiently to cause the roller to pass entirely over the face of the target. 80

The operation of the device is as follows: Assuming that the parts are in the positions shown in Fig. 4, wherein it will be noted that the rolls K bear against the rear face of the target, while the roller H stands slightly away 85

from the forward face thereof, the attendant or marksman elevates the bail I. The slightest upward movement thereof causes the cover E, with the roller H, to swing about the ends 5 J of the bail as a pivot, thereby causing the roller H to come into contact with the face of the target and the upper inner edge of the cover to swing away therefrom, as is clearly indicated in Fig. 5. In other words, the cover 10 will tend to swing down about the bail ends J as a pivotal point, the swinging movement being limited only by the contact of the roller H with the face of the target. This position of the parts will be maintained throughout 15 the course of travel of the roller up and down the face of the target, and not until the cover comes into contact with the upper edge of the receptacle will its upper edge close against the target and the roller be removed from 20 contact therewith.

It is of course immaterial whether the particular form of cover shown be employed or whether the exact pivotal connection thereof to the elevating-bail be used when the invention 25 is considered in its broadest sense. So long as the gravitating cover and roller-carrier is present and acts in the manner specified the structure may be held to fall within the scope of my invention. Any automatic- 30 ally-operated cover acting in conjunction with a painting or effacing device I deem likewise to be embraced by my invention.

It will be noted that by the employment of a bail or loop no part of the roller-operating 35 mechanism interferes with the bull's-eye, alarm, or any figure which may be employed in connection with said bull's-eye.

As will be most clearly seen upon reference to Fig. 3, the depending arms of the bail are 40 located near the outer edges of the target and are thus free from conflict with the spring-arm which carries the bull's-eye and alarm. Furthermore, by reason of the fact that the elevating-string or the like is attached to the 45 central portion of the cross member of the bail and is at a considerable distance above the roller and the cover attached to the lower end of the bail the parts will maintain a horizontal position when elevated by the string, 50 no equalizing device being necessary to insure that both ends of the cover and roller are moved up the same distance.

It will of course be understood that the rolls may be omitted from the ends of the bail 55 and the device still be successfully operated. Their presence, however, is preferable.

Having thus described my invention, what I claim, and desire to secure by Letters Patent, is—

60 1. In combination with a target; a liquid-containing trough or receptacle located adjacent thereto; an effacing device normally occupying a position within said receptacle; means for elevating and lowering said device, 65 thus causing it to pass over the face of the

target; and a closure, which when the effacing device is within the receptacle automatically closes the same.

2. In combination with a target; a liquid-containing trough or receptacle located adjacent thereto; an effacing device normally occupying a position within said receptacle; a closure for said receptacle; and means for raising and lowering said effacing device and closure, whereby the latter will effectually 75 protect the receptacle and the effacing device therein when the parts are lowered.

3. In combination with a target; a liquid-containing trough or receptacle located adjacent thereto in line with its face; a cover for 80 said receptacle; an effacing device carried by said cover; and means for raising and lowering the cover and effacing device, causing the cover to move away from the face of the target as the effacing device comes into contact 85 therewith.

4. In combination with a target; a liquid-containing trough or receptacle in line with the face thereof; a gravitating cover for said receptacle; an effacing device carried by said 90 cover; and means for elevating the cover, permitting it to swing away from the face of the target and the effacing device to come into contact with said face, substantially as described.

5. In combination with a target; a liquid-containing trough or receptacle in line with the face thereof; a cover for said receptacle, said cover having members extending rearwardly of the target; an effacing device carried by said cover; and means connected to 100 said rearwardly-extending members for elevating and lowering the cover and effacing device.

6. In combination with a target; a liquid-containing trough or receptacle located in line with the face thereof; a cover for said receptacle, said cover when closed resting at its forward edge upon the receptacle and inclining upwardly toward and bearing against the 105 face of the target; an effacing device carried by the cover; members extending rearwardly from the cover; means for holding the cover against forward movement; and means pivotally connected to said rearward extensions 110 for elevating and lowering the cover and effacing device.

7. In combination with a target; a liquid-containing receptacle in line with the forward face thereof; a cover normally closing over 115 said receptacle and bearing against the face of the target; an effacing device carried by said cover; members extending from said cover rearwardly of the target; means connected to said members for elevating said cover; and rolls bearing upon the rear face of the target and preventing a forward movement of the cover.

8. In combination with a target; a liquid-containing receptacle in line with the forward 120

- face thereof; a cover normally closing said receptacle and bearing against the face of the target, the upper face of said cover being inclined away from the face of the target; end 5 pieces secured to the cover, said pieces extending rearwardly of the target; a roller carried by said end pieces and normally occupying a position in the trough when the cover is lowered; a bail, the ends of which are bent laterally and pass through openings formed in said rearwardly-extending end pieces; and rolls mounted upon said lateral extensions of the bail, said rolls bearing upon the rear face of the target, substantially as described.
- 15 9. In combination with a target; a liquid-containing receptacle located adjacent thereto; a cover for said receptacle; an effacing device carried by said cover; and means for tilting and elevating the cover, whereby it will be drawn out of contact with the face of the target and the effacing device moved into contact therewith, substantially as described.
- 10 10. In combination with a target; a liquid-containing receptacle located adjacent thereto; 20 a cover for said receptacle; an effacing-roller carried by said cover, said roller occupying a position within the receptacle when the cover is closed; rolls connected to the cover and bearing upon the rear face of the target; and 25 means for elevating and tilting said cover, whereby it will be thrown out of contact with the forward face of the target and the roller moved into contact therewith, substantially as described.
- 30 11. In combination with a target; a liquid-containing receptacle in line with the forward face thereof; a cover for said receptacle having its upper face inclined away from the face of the target; an effacing device; and means 40 for elevating the effacing device and throwing the cover out of contact with the face of the target, substantially as described.
12. In combination with the body of a target; a trough or receptacle located at the lower 45 portion thereof; an effacing device; a bail or loop located in rear of the target; pivotal connections intermediate the ends of said bail or loop and the effacing device whereby the effacing device will swing into contact with the 50 face of the target when the bail is elevated; and a bull's-eye located in rear of the target intermediate the downwardly-extending members of the loop but free from contact therewith, substantially as described.
- 55 13. In combination with a target; a trough or receptacle; an effacing device normally occupying a position therein; a bail located in rear of said target, the vertically-disposed members of said bail standing adjacent to the 60 outer edges of the target and having their lower ends bent laterally; connections intermediate said ends and the effacing device; and a bull's-eye carried in rear of the target inter-

mediate the vertically-disposed members of the bail, substantially as described. 65

14. In combination with a target; a trough or receptacle; an effacing device normally occupying a position therein; a bail located in rear of the target, the upper end of said bail occupying a position adjacent to the upper 70 end of the target when the parts are in their normal positions; rolls mounted upon the laterally-bent ends of the bail, said rolls bearing upon the rear face of the target; and connections intermediate said laterally-extending 75 ends and the effacing device, substantially as described.

15. In combination with a target; an effacing device; a bail located in rear of the target, the upper end of said bail occupying a position adjacent to the upper end of the target when the parts are in their normal positions; rolls mounted upon the laterally-bent ends of the bail, said rolls bearing upon the rear face of the target; and connections intermediate 85 said laterally-extending ends and the effacing device, substantially as described.

16. In combination with a target, a trough or receptacle adjacent to the face thereof; an effacing device normally positioned in said receptacle; and a bail located in rear of the target, the ends of said bail being pivotally connected to the effacing device and serving to hold the effacing device against the face of the target, substantially as described. 95

17. In combination with a target, a trough or receptacle adjacent to the face thereof; an effacing device normally positioned in said receptacle; and a bail located in rear of the target, the upper portion of the bail standing 100 normally at or near the upper end of the target, the downwardly-extending arms thereof being located adjacent to the sides of the target, and the ends of the bail being pivotally connected to the effacing device and serving 105 to hold the effacing device against the face of the target, substantially as described.

18. In combination with a target, a liquid-receptacle located at the lower portion thereof and in line with its front face; an effacing- 110 roller located therein and normally out of contact with the target; a frame pivotally connected to the roller, extending rearwardly of the target; and means, pivotally connected to the frame in rear of the target, whereby when 115 said frame is elevated the roller will be brought into contact with the face of the target, substantially as described.

In testimony whereof I have signed my name to this specification in the presence of two sub- 120 scribing witnesses.

HENRY M. QUACKENBUSH.
